Primary Examiner—Brian N. Vinson*Assistant Examiner*—Robin V. Taylor
Attorney, Agent, or Firm—Veal & Marsh[57] **CLAIM**

The ornamental design for the vehicle-mounted game animal support, design as shown and described.

DESCRIPTION

FIG. 1 is a front perspective view of a vehicle-mounted game animal support showing my new design;

FIG. 2 is a rear perspective view thereof;

FIG. 3 is a rear elevational view thereof;

FIG. 4 is front elevational view thereof;

FIG. 5 is a side elevational view as seen from the left side of FIG. 3;

FIG. 6 is a side elevational view as seen from the right side of FIG. 3;

FIG. 7 is a top plan view thereof;

FIG. 8 is a bottom view thereof; and,

FIG. 9 is a perspective view of the present invention mounted on a vehicle which is shown in broken lines forming no part of the claimed design.
